(57) **CLAIM**

The ornamental design of a cylindrical robust bracket for gate hardware, as shown and described.

DESCRIPTION

FIG. 1 is a top view of the cylindrical robust bracket for gate operators in accordance with this invention. The broken lines showing in this figure and in the following figures are for illustrative purposes only and form no part of the claimed design;

FIG. 2 is a front elevational view of the cylindrical robust bracket for gate operators of FIG. 1;

FIG. 3 is a side elevational view thereof, the opposite side view being a mirror image thereof;

FIG. 4 is a bottom view thereof; and,

FIG. 5 is a rear elevational view thereof.
